UNITED STATES PATENT OFFICE.

CARL SANDWEG, OF LANGERFELD, NEAR BARMEN, GERMANY.

BRAIDING AND LACE-MAKING MACHINE.

Application filed July 27, 1920. Serial No. 399,436.

(GRANTED UNDER THE PROVISIONS OF THE ACT OF MARCH 3, 1921, 41 STAT. L., 1313.)

To all whom it may concern:

Be it known that I, CARL SANDWEG, a citizen of the German Republic, residing at Langerfeld, near Barmen, Rhenish Prussia, Germany, have invented certain new and useful Improvements in Braiding and Lace-Making Machines, of which the following is a specification.

The invention relates to a so-called single thread braiding or lace-making machine of the kind wherein the quoits or circle plates serve as drivers while the switches usually present are omitted entirely, and these plates are actuated only when the bobbins are to be advanced. The invention consists in this that on the outer or inner side or on both sides of the main track there are drivers arrestable at each quarter turn; each V-like portion of the track which extends between adjacent driving plates is made convertible into a triangular track by the provision of openable and closable passage-ways connecting the upper ends of the V, which passage-ways, when all are opened, form with the 25 sinuous raceway circuit. These passage-ways are formed and controlled by slide members, the passage of bobbins through them being effected by driving members, said slides and members being governed by the 30 pattern gear.

The quoits are arranged in pairs, the direction of rotation of successive quoits being reversed.

Moreover, the machine can be so designed that by means of these new tracks the bobbins can be advanced in the same direction on to the next plate and be guided back on to the previous plate. To obtain this motion of the bobbins by means of the new tracks, suitable rings of drivers are provided, which rings continuously circulate on the corresponding side of the main track and the various drivers of which can be individually thrown into action to drive the bobbins at the proper moment by means of the pattern gear.

Owing to the new modification in construction of the machine, the variety of patterns producible thereon is considerably increased.

This machine has been patented in Germany, No. 331,054, February 27, 1919; France, No. 519,635, July 8, 1920; England,

No. 148,330 filed July 9, 1920; Switzerland, No. 92,673, July 17, 1920, and Netherlands 55 filed Sept. 9, 1919 patent not yet granted.

I am aware that in braiding machines it has been proposed to provide auxiliary plates adjacent to one another and the main plates, and so forming an auxiliary track for the 60 bobbins. In contradistinction to this, according to the present invention, auxiliary bobbin tracks are formed by the conversion of V-like track portions into triangular track portions in the manner above described 65

The invention is illustrated by way of example in the drawing, wherein—

Fig. 1 shows a portion of the machine in plan, part of the track plate being broken away;

Fig. 2 is a section on line A—A in Fig. 1;

Fig. 3 is a view below Fig. 1, with the driving wheels omitted and

Fig. 4 a section on line B—B in Fig. 1.

The quoits or plates 1 of the braiding machine which constitute drivers are arranged as usual to be rotatable and are laid out in a circle to form the track. They are fitted as closely as possible in corresponding apertures in the track plate 2 and are provided with four bobbin-notches (i. e. bobbin-driving notches) *a*, *b*, *c* and *d* spaced apart 90°. They are rotated each by its individual pinion 3 by means of a coupling 4 so arranged and controlled by the pattern gear 85 that they can be arrested at any quarter-turn. Moreover, they are arranged so closely alongside one another that any plate when rotated may engage in the bobbin-notches of its two neighbors and they thus at the same 90 time direct the bobbins to the crossing-places. The bobbin-notches of each plate are thus capable of coacting with arcuate track-portions (as portion 40, 41, 42) on opposite sides of the aforesaid apertures, whereby a 95 bobbin engaged by the notch may be driven from one crossing-place (as *a*) to the next (as *c*).

Now according to the invention on, for example, the outer side of the main track, 100 each V-like track-portion (as 50, 50') which extends between adjacent plates 1 (i. e. the cusp-like track-portion formed at the meeting of the adjacent arcuate track-portions) is made convertible into a track by the provision of an openable and closable passage-

way 6 connecting the upper ends of the V, shown closed at the right in Fig. 1. These passage-ways open into the bobbin-notches of plates 1 which have been arrested in suitable positions and form with these bobbin-notches a ring-formed additional track running around the usual braiding track, through which additional track the bobbins may be conducted when the pattern requires it.

Where the V-like track-portions are provided with passageways, it is customary to omit the pointed portions of the track-plate 2 as heretofore usually formed, and to mount said pointed portions 5 at a lower level whereby they constitute track-portions for the bobbins by engaging the bobbin spindles below their flanges instead of between them. Said portions 5 are held by standards 7 fastened on the lower plate 8 of the machine.

Coacting with the passage-ways 6 are slides 9 which are guided in the track-plate 2 and normally may be slid up to the usual track, blocking the passage-ways 6 in their advanced positions. The slides 9 are actuated each by means of an angle-lever 10 and a pattern gear draw-rod 11 attached to the latter together with a retracting spring 12 which tends to hold the slide 9 in its advanced position, that is, in its blocking position (Fig. 1, right).

The bobbins are moved through the passage-ways 6 and the bobbin-notches of the arrested driver-plates 1, i. e. through the circular track formed around the usual track, by means of rings of driving members 13. In the embodiment by way of example, these members are mounted in two flat rings 15 and 16 which are located one above the other and guided on a series of standards 14, which rings surround the entire braiding track and are given a continuous circular movement. The lower ring 15 is guided by standards 14 themselves, and the upper ring 16 by guide-screws 17 inserted in the track-plate 2 and engaging an annular groove of the ring 16. The two flat rings 15 and 16 have circular motion in opposite directions and are given this movement by toothed wheels 18 and 19 which mesh with a circular rack in the rings.

In these two flat rings 15 and 16 are mounted the radially extending driving members 13, so that one set circulates to the right and the other set to the left and consequently when they are shifted in, the bobbins move in the particular direction in the aforesaid ring-formed track. The driving members 13 are slidable in the flat rings 15, 16 and subjected to the pull of springs 20 which tend to hold them in the position wherein they are withdrawn from the track, that is, are shifted out of engagement, so that they cannot actuate the bobbins. They are shifted into engagement by means of the

pattern gear. For this purpose are provided the eccentrically formed guides 21 and 22 on which the driving-members 13 can run by means of rollers 23 at their extreme ends, so that in that way, the driving-members 13 are gradually advanced against the action of the springs 20 and thus shifted into the track of the bobbin in order to drive same. The eccentric guides of which those indicated by 21 moving to the left act on driving-members and those by 22 on driving-members circulating in the opposite direction are each secured by a pin 24 or 25, which can move up or down in the track-plate 2 and the lower plate 8, and are normally held in their upper position by means of springs 26, in which position these eccentric guides 21, 22 are located above the path of the driving-members 13 coacting with them. Below the bottom plate 8 a bell crank lever 27 of the pattern gear engages these pins 24, 25, so that by means of said gear at a suitable moment the guides 21, 22 can be lowered into the path of the driving-members 13 to shift them into engagement.

Finally, each driving-member 13 has on it a locking lug 28, and cooperating with these lugs are locking bars 29 and 30 bent together into circular form, of which bars the bar 29, cooperating with the driving-members of the flat ring 16, is arranged on the outside of the latter and is fastened to the track-plate 2, while the other bar 30 is held on the inside of the standards 14. In a corresponding manner the locking lugs 28 are arranged on the driving-members 13, on one at the outside, and on the other at the inside end. The locking bars 29, 30 at places opposite the guides 21 or 22 are provided with recesses 31, which enable the driving members to be shifted in and out at these places. With further rotation, however, the driving-members 13 which at the time have been shifted engage, by means of their locking lugs 28, behind the rail 29 or 30 whereby they can thus be retained in the shifted-in position, but the guides 21, 22 can be again shifted out of engagement in order to relieve the pattern gear.

The bobbins *g*, *g*, have disks or flanges which extend beyond the margins of the passage ways 6. The upper gear 19 that meshes with teeth 16^b to one side of the recess 16^a in the upper ring 16 is driven by a shaft 19^a, and the lower ring 15 is driven by a shaft 18^a which carries a gear 18 in mesh with teeth 15^a in said lower ring. The horizontal pinions or series of intermeshing gears 3 have clutch faces 4^a which are adapted to be engaged by slideable clutches 4 which slide in sleeves 3^a, the couplings 4 being engaged by a member attached to vertically movable rods 4^c, which carry above the lower plate springs 4^e, said rods being 120

connected to bell cranks which are maintained by pins 4^b, said cranks being actuated by rods 4^c.

The margin of the way 6 between each of 5 the alternate concave portions has convex recesses *e* with which aline the projecting convex portions *f* of the quoit or circle plates, to close the way when opposite there- 10 to, and when one of these projecting convex portions of the quoit or circle plates, as *f* or 42, is above the concave margins 50 and 51 of the points 5, a bobbin may be moved in the way 6 to the next quoit plate.

As follows from the above description, in 15 this machine the bobbins can be conducted by means of the pattern gear either over the usual braiding track by means of the driving plates 1 or by means of the driving-members 13, through the special track 20 formed around the usual track. In the latter case the bobbins can be advanced in the usual direction of motion or be moved back in the opposite direction, according as the driving-members of the first ring 15 or those 25 of the ring 16 come into action. As already mentioned in the introduction, the special ring-formed track might be formed on the inside instead of on the outside of the main track or such a track might be provided on 30 each side. Finally, the machine could be so designed that the bobbins could move through the ring-formed track only in one direction, in which case, of course, one ring of driving-members will be omitted.

If desired, by suitably constructing the 35 machine, the passage-ways 6 which cross the trackplate points might also be utilized for arresting the bobbins therein and thus for allowing bobbins on the main track to pass 40 by.

Finally, it should be stated that the rings of driving-members might be arranged in a 45 different manner. For example, the flat rings 15 and 16 might be replaced by suitably guided chains, similar to the formerly much used pattern gear chains, in which the driving-members 13 themselves would have to be arranged so as to be capable of being 50 suitably shifted in and out.

Claims:

1. In a braiding or lace making machine, a main track consisting of a track-plate, track-plate points and driving plates arranged in recesses of said track-plate, said 55 driving plates being provided with four driving notches each, means for rotating said driving plates and for arresting them at each quarter turn, passage ways trans- 60 versely intersecting or crossing the track- plate points on one side of said main track and forming with the driving notches of the driving plates a circuitous auxiliary track in which the braiding carriers may be transferred from one driving plate of the main 65 track to another without crossing braiding

carriers located on the main track, said passage ways being openable and closable by slides controlled by the pattern gear.

2. In a braiding or lace making machine, a main track consisting of a track-plate, 70 track-plate points and driving plates arranged in recesses of said track-plate, said driving plates being provided with four driving notches each, means for rotating said driving plates and for arresting them 75 at each quarter turn, passage ways trans- versely intersecting or crossing the track- plate points on one side of said main track and forming with the driving notches of said driving plates a circuitous auxiliary 80 track in which the braiding carriers may be transferred from one driving plate of the main track to another without crossing braiding carriers located on the main track, 85 said passage ways being openable and closable by slides controlled by the pattern gear, rings of circulating driving members for moving the braiding carriers through said auxiliary track, and pattern gear controlled means for shifting said driving members in 90 and out independently of one another.

3. In a braiding or lace making machine, a main track consisting of a track-plate, track-plate points and driving plates arranged in recesses of said track-plate, said 95 driving plates being provided with four driving notches each, means for rotating said driving plates and for arresting them at each quarter turn, passage ways trans- versely intersecting or crossing the track- plate points on one side of said main track and forming with the driving notches of the driving plates a circuitous auxiliary track in which the braiding carriers may be transferred from one driving plate of the 100 main track to another without crossing braiding carriers located on the main track, said passage ways being openable and closable by slides controlled by the pattern gear, two rings of driving members circulating 105 in opposite directions for moving the braiding carriers forwards and backwards in said auxiliary track, and pattern gear controlled means for shifting said driving members in and out independently of one another. 110

4. In a braiding or lace making machine, a main track consisting of a track-plate, track-plate points and driving plates arranged in recesses of said track-plate, said driving plates being provided with four 120 driving notches each, means for rotating said driving plates and for arresting them at each quarter turn, passage ways trans- versely intersecting or crossing the track- plate points on one side of said main track and forming with the driving notches of said driving plates a circuitous auxiliary track in which the braiding carriers may be transferred from one driving plate of the main 125 track to another without crossing braiding 130

braiding carriers located on the main track, said passage ways being openable and closable by slides controlled by the pattern gear, driving members slidably mounted in circulating rings for moving the braiding carriers through said auxiliary track, springs normally holding said driving members in their inoperative position, and eccentrically formed pressure-cheeks controlled by the pattern gear for shifting said driving members into their operative positions.

5. In a braiding or lace making machine, a main track consisting of a track-plate, track-plate points and driving plates arranged in recesses of said track-plate, said driving plates being provided with four driving notches each, means for rotating said driving plates and for arresting them at each quarter turn, passage ways transversely intersecting or crossing the track-plate points on one side of said main track and forming with the driving notches of said driving plates a circuitous auxiliary track in which the braiding carriers may be transferred

from one driving plate of said main track 25 to another without crossing braiding carriers located on the main track, said passage ways being openable and closable by slides controlled by the pattern gear, driving members slidably mounted in circulating rings 30 for moving the braiding carriers through said auxiliary track, springs normally holding said driving members in their inoperative positions, eccentrically formed pressure-cheeks controlled by the pattern gear 35 for shifting said driving members into their operative positions, locking lugs on said driving members, and rigidly mounted locking bars adapted to co-operate with said locking lugs for holding said driving members in operative positions, said locking bars being at certain places opposite said pressure-cheeks provided with recesses through which said locking lugs may pass.

In testimony whereof I hereunto affix my 45 signature.

CARL SANDWEG.
